[57] CLAIM

The ornamental design for a resealing closure, as shown and described.

DESCRIPTION

FIG. 1 is a top plan view of a resealing closure showing my new design;

FIG. 2 is a side elevational view thereof;

FIG. 3 is a bottom plan view thereof;

FIG. 4 is a sectional view looking in the direction of arrows 4—4 of FIG. 1 thereof;

FIG. 5 is a sectional view looking in the direction of arrows 5—5 of FIG. 1 thereof;

FIG. 6 is a top plan view of a modified form of my new design;

FIG. 7 is a side elevational view thereof;

FIG. 8 is a bottom plan view thereof;

FIG. 9 is a sectional view looking in the direction of arrows 9—9 of FIG. 6 thereof; and,

FIG. 10 is a sectional view looking in the direction of arrows 10—10 of FIG. 6 thereof.
